(57) **CLAIM**

The ornamental design for an inhaling device, as shown and described.

DESCRIPTION

FIG. 1 is a rear perspective view of the present inhaling device;

FIG. 2 is a front perspective view of same;

FIG. 3 is a top view of the inhaling device of FIG. 1;

FIG. 4 is a bottom view of same;

FIG. 5 is a left side view of the inhaling device of FIG. 1;

FIG. 6 is a right side view of same;

FIG. 7 is a front view of the inhaling device of FIG. 1; and,

FIG. 8 is a rear view of same.

The broken lines in the drawings depict portions of the inhaling device that form no part of the claimed design.
